CLAIM

We claim the ornamental design for a printer interface, as shown and described.

DESCRIPTION

FIG. 1 is a top perspective view of a printer interface;
FIG. 2 is an enlarged fragmentary top plan view thereof;
FIG. 3 is an enlarged fragmentary front elevational view thereof;

FIG. 4 is an enlarged fragmentary right side elevational view thereof;

FIG. 5 is an enlarged fragmentary left side elevational view thereof; and,

FIG. 6 is an enlarged fragmentary perspective view of the printer interface showing the top position in an alternative position.

The broken lines in the drawings are directed to environment and are for illustrative purposes only; forming no part of the claimed design.
